[57] CLAIM

The ornamental design for a equipment console, as shown and described.

DESCRIPTION

FIG. 1 is a perspective view of an equipment console showing my new design;

FIG. 2 is a top elevational view thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a bottom elevational view thereof;

FIG. 8 is a perspective view of a dual keyboard alternate embodiment of the equipment console of the invention.

The rear and bottom views of the alternate embodiment of FIG. 8 is the same as FIGS. 5 and 7, respectively.

FIG. 1

FIG. 2
